GASOLINE TREATING

John Matthias Cranmer, East Providence, R. I., assignor to Socony-Vacuum Oil Company, Incorporated, New York, N. Y., a corporation of New York

Application March 1, 1950, Serial No. 147,088

6 Claims. (Cl. 196—32)

1

The present invention relates to the treatment of gasoline and other light petroleum products containing mercaptans and more particularly to an improvement in the processes for treating gasoline and other low boiling petroleum products to remove mercaptans and provide a finished product having a lowered disulfide content.

The art is well acquainted with the various methods for removing mercaptans from gasoline and other light fractions of petroleum including kerosene and the like. In general these methods for producing gasoline and the like having a low mercaptan content comprise contacting the hydrocarbon mixture with an alkaline solution which contains or can be devoid of solutizers such as alkali metal isobutyrate, alkali metal alkyl phenolates and others well known to the art to remove a major portion of the mercaptan content of the untreated hydrocarbon mixture and to provide a mixture of hydrocarbons having a lowered mercaptan content.

The importance of the removal of mercaptans from gasoline, in particular, has increased with the greater demand for gasolines of high octane or high anti-knock rating due to the fact that the increase in octane rating obtained by the addition of tetra-ethyl lead is decreased by the presence of mercaptans in the finished gasoline. The methods presently employed to remove mercaptans from gasoline and the like are ineffective for the removal of disulfides which are the oxidation products of the mercaptans originally present in the gasoline. Consequently, whenever a portion of the mercaptans present in the gasoline is converted to disulfides prior to or during treatment for the removal of mercaptans, that portion of the mercaptan content of the gasoline which has been converted to disulfides is not removed from the gasoline and remains in the treated gasoline. These disulfides are equally harmful in that they diminish the effect of the addition of tetra-ethyl lead. In fact, some evidence has been offered to support the view that disulfides are more effective in reducing the effect of tetra-ethyl lead upon the octane rating than the mercaptans from which they are derived. It has now been discovered that gasoline and other mixtures of hydrocarbons containing mercaptans which prior to or during treatment are subjected to conditions under which oxidation of the mercaptans to disulfides takes place may be treated to inhibit this oxidation and provide a gasoline of lowered disulfide content. In conjunction with the treatment to inhibit this internal oxidation, it is also desirable to treat the

2

extraction solution in such a manner as to reduce the disulfide content of the extracting solution at least to a level which provides a low reentry value for the disulfides.

Among the more recent methods for treating gasoline to remove mercaptans is the tannin solutizer process. The tannin solutizer process comprises treating the sour gasoline; i. e., gasoline containing more than 0.0004 per cent sulfur as mercaptan sulfur with an aqueous alkaline solution containing a solutizer and a phenolic oxidation promoter such as polyhydroxy benzenes, tannic acid, tannins and picramic acid. After contact with the sour gasoline, the aqueous solution is separated from the gasoline, and regenerated by passing air or other gas containing free oxygen through the fouled aqueous alkaline solution at temperatures of the order of about 130° F. As a result of this treatment the mercaptans which were originally present in the gasoline and are present in the aqueous solution as mercaptides are oxidized to disulfides, a major portion of which can be separated from the aqueous alkaline solution by settling and decantation. However, these disulfides have a determinable solubility in the aqueous alkaline solutions and as a consequence the disulfide content of the regenerated aqueous alkaline solution builds up to a point where in contact with fresh, sour gasoline results in the extraction of disulfides from the aqueous solution by the sour gasoline. This definitely can be overcome by washing the regenerated aqueous alkaline solution with a petroleum fraction to extract the disulfides before the regenerated aqueous alkaline solution is contacted with fresh, sour gasoline. In general, the disulfide content of the regenerated aqueous alkaline solution is kept below about one-two per cent disulfide sulfur and preferably about 0.1 to 0.3 per cent disulfide sulfur. Although removal of the disulfides from the regenerated aqueous alkaline solution lowers the disulfide content of the treated gasoline, an undesirable amount of mercaptans are converted to disulfides prior to or during contact with the aqueous alkaline solution. Since these disulfides are more soluble in the gasoline than in the aqueous alkaline solution, the aqueous alkaline solution does not extract the disulfides and they remain in the gasoline to increase the amount of tetra-ethyl lead, which must be added per unit of gasoline to produce the desired octane rating. Since the disulfides produced in this manner arise from the oxidation of a portion of the original mercaptan content of the gasoline, it is desirable, and in fact necessary, in order to

obtain the highest octane rating for a particular gasoline with the lowest addition of tetra-ethyl lead to inhibit the oxidation of the mercaptans or to eliminate it entirely.

Therefore, it is an object of the present invention to provide a method for inhibiting the internal oxidation of the mercaptans in sour gasoline prior to or during treatment with aqueous alkaline solutions for the removal of mercaptans.

It is another object of the present invention to provide a method for producing gasoline having a lowered disulfide content by inhibiting internal oxidation and by reducing the disulfide re-entry value of the regenerated aqueous alkaline mercaptan extracting solution.

Other objects and advantages will become apparent from the following discussion taken in conjunction with the drawing. In general the aforesaid objects can be accomplished by passing the gasoline directly from the stabilizer to a pre-wash step and then to the mercaptan extracting system and injecting an internal oxidation inhibitor into the gasoline immediately after removal from the stabilizer. The internal oxidation inhibitor preferably is an organic substance soluble in the mixture of hydrocarbons, for example, gasoline, and having a higher oxidation potential than the mercaptans of the hydrocarbon mixture. In other words, the inhibitor of internal oxidation is an organic substance soluble in the hydrocarbon mixture which is more readily oxidized than the mercaptans of the hydrocarbon mixture. A satisfactory internal oxidation inhibitor is N,N'-di(secondary-butyl)-phenylenediamine available industrially as U. O. P. #5 or Dupont #22. Other internal oxidation inhibitors are N,N'-di(normal-butyl)-para-phenylenediamine, N,N'-di(iso-butyl)-para-phenylenediamine, 2,4-dimethyl-6-tertiary-butyl phenol and 2,6-di(tertiary butyl)-4-methyl phenol.

In order that those skilled in the art may have a better understanding of the present invention, the use of an internal oxidation inhibitor in the production of gasoline with an increased sensitivity to tetra-ethyl lead will be described in conjunction with the drawing. Gasoline from a stabilizer (not shown) drawn through line 1 to pre-washer 2. At some point, say 3, on line 1 upstream from the pre-washer 2 an internal oxidation inhibitor such as the aforementioned N,N'-di(secondary-butyl)phenylenediamine is introduced through conduit 4 by pump 5 from storage tank 6. As those skilled in the art know, pre-washer 2 contains an aqueous solution of alkali metal hydroxide of such strength as to remove hydrogen sulfide and light mercaptans such as methyl and ethyl mercaptans. When the composition of the sour gasoline is such as to make it desirable, the pre-washer can be bi-passed and the gasoline containing the internal oxidation inhibitor can be introduced directly into extractor 12 through lines 9 and 11 by closing valve 7 and opening valves 8 and 10. When the gasoline containing the internal oxidation inhibitor is passed through the pre-washer, the pre-washed gasoline enters line 11 and passes to extractor 12 where it is contacted as it rises therein with an aqueous alkaline solution preferably containing a solutizer such as an alkali metal alkyl phenolate introduced into extractor 12 through line 13. In a multi-stage extraction, which is usually required, the aqueous alkaline solution introduced into extractor 12 through line 13 is drawn from extractor 14 through line 15. The aqueous al-

kaline solution after passing through extractor 12 is withdrawn therefrom through line 16 and introduced into the regenerator 17 wherein air is introduced through line 32 in sufficient quantity to oxidize substantially all of the mercaptide present in the aqueous alkaline solution but when desirable to leave sufficient unoxidized mercaptan to prevent inactivation of the oxidation promoter. The excess air and any mercaptans which may be vaporized escape from regenerator 17 through vent 18. The regenerated solution is withdrawn from regenerator 17 through line 19 to settler 20 where the disulfides settle out as an upper layer and are withdrawn through line 21 to storage or for admixture with cracking stock or for admixture with fuel. The lower aqueous alkaline layer in settler 20 is withdrawn through line 22 to disulfide extractor 23 into which hydrocarbon solvent for disulfides, such as naphtha boiling within the range about 180° to about 450° F. or having a boiling range of about 80° to about 450° F. or in general a hydrocarbon mixture boiling within the range about 500° and about 750° F., is introduced through line 24. The hydrocarbon solvent rising through the regenerated aqueous alkaline solution extracts the disulfides therein and is withdrawn from the disulfide extractor 23 through line 25. The extracted regenerated aqueous alkaline solution is withdrawn from extractor 23 through line 26 and introduced into the last stage of the mercaptan removal system extractor 14. The partially demercaptanized gasoline after treatment in extractor 12 passes through line 27 into extractor 14 and rises through the lean extracted regenerated aqueous alkaline solution and leaves extractor 14 through pipe 28 to be introduced into water washer 29 into which water is introduced through conduit 30 and from which water is withdrawn through pipe 31 while the water washed demercaptanized gasoline leaves the water washer 29 through line 32 to a storage or distribution system.

Those skilled in the art will understand that one or more mercaptan extractors can be interposed between extractor 12 and 14 of the drawing and the aqueous alkaline solution passed through these additional extractors in series therewith and countercurrent to the flowing stream of hydrocarbons being demercaptanized. Those skilled in the art will also understand that a portion of the fouled aqueous alkaline solution; i. e., aqueous alkaline solution containing extracted mercaptans can be removed from extractor 14 through line 33 under the control of valve 33 and regenerated when desired. Other variations in the manipulation of the stream or streams of gasoline or other hydrocarbon mixtures containing the internal oxidation inhibitor can be used without departing from the spirit of this invention.

In general the internal oxidation inhibitor is employed in amounts effective to reduce or eliminate the internal oxidation of the mercaptans in the gasoline to disulfides. It has been found that from 5 to about 20 pounds of inhibitor per thousand barrels of sour gasoline provides satisfactory results. However, it is preferred to use about 8 to about 12 or 15 pounds of inhibitor per thousand barrels of gasoline. Highly satisfactory results have been obtained by using 10 pounds of N,N'-di(secondary-butyl)phenylenediamine per thousand barrels of sour gasoline. It is also desirable to transfer the sour gasoline from the stabilizer or from storage in a closed system so

that the amount of oxygen absorbed by the gasoline is kept at a minimum.

I claim:

1. A method of inhibiting internal oxidation of mercaptans to polysulfides in gasoline which comprises drawing gasoline containing mercaptans from a stabilizer, introducing about 5 to about 20 pounds of N,N'-di(secondary-butyl) phenylenediamine per 1,000 barrels of gasoline into said gasoline, contacting said gasoline containing mercaptans and said phenylenediamine in the absence of substantial amounts of air with an alkaline solution to extract a major portion of said mercaptans to obtain a fouled alkaline solution containing said extracted mercaptans as mercaptides and a treated gasoline, separating said treated gasoline from said fouled alkaline solution, and regenerating said fouled alkaline solution.

2. A method of inhibiting internal oxidation of mercaptans to polysulfides in gasoline which comprises introducing about 5 to about 20 pounds of N,N'-di(secondary-butyl) phenylenediamine into about 1,000 barrels of gasoline containing mercaptans, contacting said gasoline containing mercaptans and said phenylenediamine in the absence of substantial amounts of air with an alkaline solution to extract said mercaptans and obtain a fouled alkaline solution containing extracted mercaptans as mercaptides, separating said fouled alkaline solution from treated gasoline, passing air through said separated fouled alkaline solution to convert said mercaptides to polysulfides, separating said polysulfides from said alkaline solution, and contacting said alkaline solution in the absence of substantial amounts of air with further amounts of gasoline containing mercaptans and about 5 to about 20 pounds of N,N'-di(secondary-butyl) phenylenediamine.

3. The method set forth and described in claim 2 wherein the alkaline solution after separation of the polysulfides is extracted with an immiscible organic solvent for polysulfides and the solvent separated from the alkaline solution.

4. A method of inhibiting internal oxidation of mercaptans to polysulfides in a hydrocarbon mixture which comprises introducing into a hydrocarbon mixture containing mercaptans about 5 to about 20 pounds per 1,000 barrels of said hydrocarbon mixture of an organic compound soluble in said hydrocarbon mixture and being more readily oxidized than said mercaptans, contacting said hydrocarbon mixture containing mercaptans and said organic compound in the absence of substantial amounts of air with an alkaline solution to extract said mercaptans and obtain a fouled alkaline solution containing extracted mercaptans, separating said fouled alkaline solution from treated hydrocarbon mixture, passing air through said separated fouled alkaline solution to convert mercaptans present therein as mercaptides to polysulfides, separating said polysulfides from said alkaline solution, to obtain a regenerated alkaline solution and contacting further amounts of hydrocarbon mixture containing mercaptans and about 5 to about 20 pounds of said organic compound in the absence of substantial amounts of air with said regenerated alkaline solution.

5. The method of inhibiting internal oxidation of mercaptans to polysulfides in a hydrocarbon mixture as set forth and described in claim 4 wherein the regenerated alkaline solution is extracted with an immiscible solvent for polysulfides and said immiscible solvent separated from said regenerated alkaline solution.

6. The method of inhibiting internal oxidation of mercaptans to polysulfides in a hydrocarbon mixture as set forth and described in claim 4 wherein the organic compound more readily oxidized than mercaptans is N,N'-di(secondary-butyl) phenylenediamine and the regenerated alkaline solution is extracted with a petroleum fraction.
